BRANCHED STREAM CONTROL

Clinton L. Savidge, Toledo, Ohio, assignor to
 Mitchell & Smith, Inc., Detroit, Mich., a corporation of Massachusetts

Application December 27, 1943, Serial No. 515,864

2 Claims. (Cl. 49—55)

This invention relates to flowing molten material with controls for stream dimension and temperature.

This invention has utility when incorporated in conjunction with fiber or blow nozzles, and involves stream subdivider means for the respective nozzle capacities for thereby building up to take greater volume from the molten stream source or cupola. Appropriate temperature drop or rise, effected by the stream directing or subdividing channels, is herein worked out for such stability in the control as to contribute to ease in maintenance of uniformity of product at a high tonnage rate.

Referring to the drawing:

Fig. 1 is a front view, with parts broken away, of a cupola having its take-off stream or flow to subdivider stream control embodying features of the invention herein;

Fig. 2 is an enlarged view of the stream divider from the right in Fig. 1;

Fig. 3 is a perspective view of a divider receiving one stream and uniformly converting such single stream into four branches;

Fig. 4 is a section on the line IV—IV, Fig. 1, showing the chambered structure for handling therethru a temperature controlling medium; and

Fig. 5 shows a gang of subdividers in series parallel relation.

A cylindrical cupola 1 is shown with an opening 2 into which is mounted facing means 3 having therein a draw-off port 4 for a stream 5. In the practice of producing mineral wool, as from slag or various rocks, care may be exercised in providing the ingredients for a prescribed or predetermined type of melt. Upon stabilizing such factors, there is efficiency in operating the cupola at maximum rate for fusing with timely flowing-off or withdrawal, as important economies for production cost reduction. The experience has been that it is advantageous in the drawing-off to have but a single port. At high fluxing temperatures, the molten glass-like stream has a high flow rate. Such stream is readily retarded into a syrupy mass before congealing. Accordingly, under the practices herein, there is delicate regulation which may only slightly lag the stream as delivered to the nozzle, but still retain the uniform fluidity to receive the blowing by the steam into threads and thereby avoiding fine glass globules or beads or seeds.

Accordingly from legs or supports 6 for the cupola 1 adjustable bolt mounting means 7 locate a supporting angle metal member 8 below the port 4. Screws 9 anchor a stream divider 10 in

position close up to the port 4. The flowing stream 5 over a lip 11 adjacent the port 4 is into a minor chamber, pocket, or reservoir 12 in top 13 region of the chambered divider member 10. From the reservoir 12 it is important to have branches equalized under the preferred practice hereunder, and that such be approximately equally spaced. For directing these branches, applicant has found it helpful to have such branches not entirely free falling, but at least to some extent directed and supported in the spreading flow directions. The member 10 is shown with a pair of front grooves or subdivided stream ways 14 and two end ways 15. Notches in the top 13 extend to slight lips 16 to dam a shallow volume of molten material in the reservoir 12 against flow thereto into the respective ways 14, 15. Top section 17, between the front ways 14 is the full height to minimize tendency of the flowing stream to splash outward.

At starting, or sometimes in used, chilled or non-flowing particles lodge in the reservoir 12. By providing lower corners 18 than the top 13, 17, more ready access is had to clear the reservoir 12 as well as to observe that it be functioning properly. With the grooves 15 at approximately 60° slant there is considerably more support as well as temperature control than for the grooves 14 of approximately half the slant for the grooves 15. This means that spray or fiber nozzles 19 are spaced somewhat lower or farther from the grooves 14 than are fiber nozzles 20 for the streams from the grooves 15. The respective nozzles 19, 20, are adjusted and properly directed in their location upon a support, and are individually regulated as to the steam or fiber effecting fluid by valves from a main supply duct or pipe 23.

Supplementally a temperature controlling medium, as water, may have flow thereof regulated by a valve 24 as to the rate of flow or volume passing by the pipe 25 into a chamber 26 in the member 10. As such medium performs its function, say of cooling for the member 10, it passes therefrom as a spill by pipe 27.

With similar molten material, applicant's experience for the stream drop was 10" (Patent 2,295,971) to the nozzles. Herein the lip 11 approximately contacts the top 13, and the spacing from the spill of the grooves 15 may be 3" or even less. The clearance is sufficient to locate the proper adjustment for the nozzles 20. The nozzles 19 may have their spacing say 3½" from the grooves 14.

The member 10 quadruples the nozzle capacity for fibering the outflow from the cupola 1. For

further building up fiberizing rate, a subdivider member 28 (Fig. 5) which may or may not be chambered for temperature control, has streams 29 therefrom to members 10, and stream 30 to a three stream member 31. Accordingly with the member 28 in series with the respective members 10, 31, 10, which latter three are in parallel, eleven nozzles may be supplied with streams.

Of practical importance in the disclosure and operations herein is the stream branch volume, its direction control with limited free-fall, which under the temperature control, permits the proximity for the fiberizing nozzles so close to the groove directed stream that full fiberizing is stabilized. The furnace operation is for having the molten material fully fluid. At such free flow rate and thinness, the acute problem is to get the fiber-effecting blow effective thruout the stream, to minimize or eliminate beads or seeds of small glass-like beads. The uniform character of the melt is more readily retained at this high temperature of fluidity. By bringing about a retarding of the stream after leaving the cupola or furnace, some temperature drop is effected. With the chambered block or member providing this pool, supplemental lowering may be had from water cooling. In practice, efficient fiberizing has been achieved at 500# per hour with a nozzle. This seems to be the nozzle efficient capacity, and is effected after some drop in the temperature of the stream. If such be free falling in the open, it is sensitive to deflection, and as so developing, detracts from proper nozzle functioning. The more close connections possible hereunder have meant that as a desired operation is set up, there is uniformity between the operation of the nozzles of a group or gang, and the steam may be cut off in line 23 by a valve 32, and adjusted thereby. When it be considered that desired quality product with one nozzle be reached at 500# per hour, and that even as divided into two streams and no pool or pocket, there be required constant attention in seeking to hold a level for commercial output, there is understood the value

coming from four nozzles as stable and taking but a minimum of attention for handling 2000# per hour. Further control takes into account the melt rate or capacity for the furnace with the particular materials being fluxed. With such determined, the feeder members for branching stream control may be built up to conform thereto. This means that for the eleven stream branch set up of Fig. 5, 5500# per hour may be treated.

What is claimed and it is desired to secure by Letters Patent is:

1. In the flowing of molten material for receiving treatment, stream condition control from a flow supply comprising a member having from its top, in an adjoining series three downwardly diverging sides, there being notches in the top communicating with grooves in the respective sides, said top forming a reservoir bounded by lips at the respective notches for overflow of molten material pool in the reservoir to be by way of the notches and then downwardly and outwardly along the grooves in directing free fall approximately uniformly of streams away from the member.
2. Feeder stream control for mineral wool fiberizing nozzle treatment comprising a generally polygonal member having a reservoir in its top forming a pool-providing pocket for molten material, three downwardly diverging sides of the member having grooves extending downwardly from the top with notches in the top extending to connect the respective grooves with the reservoir, there being lips at the termini of the notches at the reservoir to retain a pool of the molten material in the reservoir with flow way for molten material above the lips as accumulating in the pool to pass thru the notches and grooves in distributed descent for free fall from the member, said member below the reservoir being provided with a chamber, and circulator means in communication with the chamber to promote material temperature control.
